UNITED STATES PATENT OFFICE.

JOHN B. DES ROSIERS, OF PROVIDENCE, RHODE ISLAND, ASSIGNEE, BY MESNE ASSIGNMENTS, TO KITAUTO COMPANY, OF PROVIDENCE, RHODE ISLAND.

ASSEMBLING TOOL.

Application filed July 27, 1923. Serial No. 654,270.

To all whom it may concern:

Be it known that I, JOHN B. DES ROSIERS, a citizen of the United States, residing at Providence, in the county of Providence and State of Rhode Island, have invented certain new and useful Improvements in Assembling Tools, of which the following is a specification.

This invention relates to an improved construction of assembling tool, more particularly employed in the assembling of certain parts of automobiles; and the object of this invention is to provide an improved construction of such a tool which consists in forming the tool in three distinct parts and connecting these parts together whereby they may be formed from a strip of metal and assembled with the minimum amount of expense.

20 A further object of the invention is to provide a bridge bar to which a pair of side arms are pivotally connected whereby the side arms may be folded when not in use, to reduce the storing and shipping space of the tool to the minimum.

With these and other objects in view, the invention consists of certain novel features of construction, as will be more fully described, and particularly pointed out in the appended claims.

In the accompanying drawings:

Figure 1 is a perspective view illustrating my improved tool as applied to the ends of a series of brake parts to hold them in position during the assembling of the parts.

40 Figure 2 is a side elevation illustrating the bridge bar to the opposite ends of which the arms of my improved device are pivotally connected, and showing the arms open in parallel operative relation.

Figure 3 is a sectional edge view showing the bridge bar with the side arms in section mounted at opposite ends and on opposite sides of said bar.

45 Figure 4 shows the arms as folded upon the bar to lie side by side.

It is found in practice in the assembling of brake parts of a certain type of motor vehicle, of great advantage to provide a U-shaped assembling tool adapted to engage the opposite ends of the several parts and hold them in alignment during the assembling operation of these parts.

55 It is also found of advantage to form

the parts of this assembling tool from a narrow strip of metal and connect together the members of the tool as by such a construction they may be made very rapidly and at small expense and there is practically no waste of the stock; and second, by this construction the parts may be folded upon themselves thereby taking up the minimum amount of space for storing and transportation; and the following is a detailed description of one construction of assembling tool by which these advantageous results may be accomplished:—

With reference to the drawings, 10 designates the bridge bar of the device which is preferably formed from a strip of sheet stock having its opposite ends 11 turned off at right angles to the plane of the body portion and in opposite directions thereby forming stop shoulders 12 for the side 70 arms 13. These side arms are preferably formed from stock of substantially the same width and thickness as that of the bridge bar, each being pivoted at 14 near the opposite ends of the bar, preferably 75 with a hollow rivet, the end of the arm about the rivet being circular permitting it to swing on its rivet from open to closed position, as illustrated in Figure 4.

80 The back edge portion of each arm adjacent the rivet is preferably laterally or rearwardly offset as at 15 forming a shoulder which is adapted to rest upon the stop edge 12 on its adjacent bent back end 11 whereby when the arm is swung to open position it is 85 positively held in proper parallel alignment with the opposite arm, and by engagement of this shoulder with this edge a shearing action on the bent back edge of the bar is 90 necessary before the arm can be forced back 95 out of its proper alignment.

By mounting the arms on tubular rivets a ring or other attaching device may be inserted into the eye, if desired.

100 My improved assembling tool is extremely simple and practical in construction, may be made practically without waste of any of the stock; may be assembled at the minimum expense; may be folded to take up the minimum space for transportation and storage and when the arms are swung to open position it forms a strong and durable tool to facilitate the assembling of the parts of a motor vehicle.

105 110 The foregoing description is directed sole-

ly towards the construction illustrated, but I desire it to be understood that I reserve the privilege of resorting to all the mechanical changes to which the device is susceptible, the invention being defined and limited only by the terms of the appended claims.

I claim:

1. An assembling tool having a bridge bar, a pair of side arms pivotally connected to said bar in spaced relation to stand parallel with each other and provide a work-engaging yoke, said arms being foldable to lie side by side.
2. An assembling tool having a bridge bar, a pair of side arms pivotally connected in spaced relation to said bar, a stop on said bar to cause said arms to stand parallel with each other when swung into operative position, and said arms being adapted to be folded inwardly toward each other.
3. An assembling tool having a bridge bar, a pair of side arms pivotally connected to opposite ends and on opposite sides of said bar, said ends being turned in opposite directions to provide a stop for its adjacent

arm whereby said arms are caused to stand substantially parallel with each other when swung to operative position.

4. An assembling tool having a bridge bar with turned back stop ends and a pair of side arms pivotally connected to opposite ends of said bar, each arm adjacent its joint having a shoulder on its back edge to engage and form a stop on its turned back bar end to limit its opening swing whereby said arms will stand parallel with each other when in operative position.

5. An assembling tool having a bridge bar and a pair of side arms, each formed from a narrow strip of metal, one end of each arm being connected to each of the opposite ends of said bar and a stop adjacent the point of connection for preventing said arms from spreading from parallel relation whereby a U-shaped tool is formed when the arms are in working position.

In testimony whereof I affix my signature.

JOHN B. DES ROSIERS.
